UNITED STATES PATENT OFFICE.

BENEDICT D. JACOVETT, OF LORAIN, OHIO.

SEWER-REFILLING TRAY.

1,395,828.

Specification of Letters Patent.

Patented Nov. 1, 1921.

Application filed April 18, 1921. Serial No. 462,367.

To all whom it may concern:

Be it known that I, BENEDICT D. JACOVETT, a citizen of the United States, residing at Lorain, in the county of Lorain and State 5 of Ohio, have invented certain new and useful Improvements in a Sewer-Refilling Tray; and I do hereby declare the following to be a full, clear, and exact description of the invention, such as will enable others 10 skilled in the art to which it appertains to make and use the same.

The object of the invention is to provide a refilling tray for use in connection with excavating operations as for example in 15 laying a sewer or the like wherein the earth is excavated and after the sewer pipe has been laid it is necessary to replace so much of the earth as the trench will receive properly settled and packed, and the particular object 20 is to facilitate the replacing of the earth after the sewer or main has been positioned, to avoid the tedious operation of shoveling; and with this object in view the invention 25 consists in a construction and combination of parts of which a preferred embodiment is shown in the drawing, wherein:

Figure 1 is a plan view of an apparatus embodying the invention.

Fig. 2 is a longitudinal sectional view of 30 the same.

Fig. 3 is a detail view of one end of one of the dumping plates and the connected links for securing the same in series.

The device consists essentially of a series 35 of dump plates 10 having terminal trunnions 11 connected in series by links 12 to form a tray of any desired extent or area, the links having openings 13 through which the trunnions extend and being held in place by 40 cotter pins 14 or the equivalent thereof.

The trunnions or axes of the dump plates are arranged at one side edge of each plate thereby leaving the other edge free for 45 swinging movement, and the dump plates are spaced by the links so that the free edge of one plate underlaps the pivotal or axial edge of the next plate to prevent material thrown upon the tray during the excavating operation from passing therethrough.

50 After the sewer pipe or main has been laid and it is desired to replace the earth in the trench or excavation a draft link 15 is connected with the draft eyes 16 at one end of the tray and either horses or a trac-

tor may be connected with the links for moving the tray toward and over the trench so that as the same extends over the opening the plates will swing downward and deposit the earth in the cavity. 55

The draft link may as illustrated be provided with terminal hooks 17 for engagement with the draft eyes 16 and before the commencement of the excavation a number of these trays may be arranged at the side of the line on which the sewer or main is 60 to be laid and obviously, as each tray is unloaded in the progressive refilling of the trench it may be carried forward along the line of the work and positioned to receive a new load. 65

Having thus described the invention, what I claim is:—

1. A refilling tray having a plurality of plates maintained in load-retaining relation by contact with the ground, and means 70 mounting the plates for relative movement to discharge the load through disengagement of the plates with the ground and weight of the load thereon as the tray spans opposed walls of a trench. 75

2. A refilling tray having a plurality of plates maintained in load-retaining relation by contact with the ground, and means 80 mounting the plates for relative movement to discharge the load through disengagement of the plates with the ground and weight of the load thereon as the tray spans opposed walls of a trench, consisting of 85 trunnions on the plates, and links pivoted on said trunnions. 90

3. A refilling tray having a plurality of plates maintained in load-retaining relation by contact with the ground, and means 95 mounting the plates for relative movement to discharge the load through disengagement of the plates with the ground and weight of the load thereon as the tray spans opposed walls of a trench, consisting of trunnions on the plates, links pivoted on said trunnions, said trays underlapping each 100 other in load-retaining relation, and draft means for the tray.

In testimony whereof I affix my signature in presence of two witnesses.

BENEDICT D. JACOVETT.

Witnesses:

LAURENCE H. JOB,
DOMINICK JACOVETT.
